UNITED STATES PATENT OFFICE

SAMUEL M. KINTNER, OF PITTSBURGH, PENNSYLVANIA, ASSIGNOR TO WESTINGHOUSE ELECTRIC & MANUFACTURING COMPANY, A CORPORATION OF PENNSYLVANIA

DUPLEX TRIODE VACUUM TUBE

Application filed August 28, 1924. Serial No. 734,603.

My invention relates to thermionic discharge devices and more particularly to a thermionic triode having a relatively large capacity.

5 An object of my invention is to produce a space discharge device having a filamentary cathode adapted to be heated by low voltage and small current and have a large electron emission.

10 Another object of my invention is to produce a space discharge device having low current, low-voltage filamentary cathodes and a plurality of anodes.

15 Another object of my invention is to produce a space discharge device having a plurality of electrodes connected in parallel.

20 Another object of my invention is to produce a space discharge device having a plurality of cathodes serially connected and a plurality of anodes parallelly connected.

25 Another object of my invention is to produce a space-current discharge device having the same operating characteristics and made from the same parts as a standard type of tube and having a higher space current.

30 Another object of my invention is to produce a space-current discharge device having a relatively high space current and utilizing, in its construction, parts similar to those of previous standard construction.

35 Another object of my invention is to produce a space discharge device having a high mutual conductance and a low inter-electrode capacity.

40 Another object of my invention is to produce a multiple arrangement of anodes, grids and cathodes mounted on a small number of press wires.

45 In the prior art of the manufacture of vacuum tubes, it has been found desirable to construct a thermionic triode having a filamentary cathode of such a size and constitution that it could be heated to an operating temperature by the current of a single dry cell.

50 In the construction of such a device, it has been found that the electron emission of a filamentary cathode sufficiently small to be heated to a working temperature by the current from a single dry cell was limited to a relatively small value.

For many purposes, this value has been found to be too small. For some of these purposes, it has been possible to utilize the space current of two devices in parallel, thereby obtaining a sufficiently large anode current. This, however, has not been wholly satisfactory because of the difficulty of constructing tubes whose performance characteristics are nearly enough alike to permit them to operate in parallel. Much care in choosing and matching the tubes has been necessary to find pairs of tubes that would operate in parallel, or elaborate connection schemes have been necessary to cause tubes of different characteristics to operate in parallel. This difficulty has been due more to differences in vacuum than to any other factors since it has been found that it is quite possible to construct the mechanical portions to the same dimensions with adequate accuracy.

55 My invention provides means whereby a space discharge device is produced having a cathode suitable for heating by dry-battery current and having the desired high electron stream and plate current. My invention consists of a structure comprising a plurality of cathode, anode and grid electrodes mounted upon single lead wires in a single press within a single container.

60 In my preferred embodiment, I use a pair of cylindrical anodes, a pair of cylindrical grids and a pair of filaments, all of the size, material and structure well known in the prior art.

65 Other objects and structural details of my invention will be apparent from the following description when read in connection with the accompanying drawings, wherein:

70 Figure 1 is a view, partially in elevation and partially in section, of a thermionic discharge device structure having a disposition of the plane containing the axes of the cylindrical anodes at right angles to the plane of the press.

75 Fig. 2 is a view, partially in elevation and partially in section, of a structure having the plane of the axes of the cylindrical anodes parallel to the plane of the press.

80 Fig. 3 is a view in horizontal section of

the device of Figure 1, taken on the line III—III,

Fig. 4 is a horizontal section of the structure of Fig. 1 taken on line IV—IV, and

5 Fig. 5 is a view in horizontal section of the structure of Fig. 2 taken on line V—V.

Referring to the figures, a container 1 is mounted on a base 2 carrying a plurality of connecting lugs 3. Container 1 has a re-

10 entrant stem portion 4 terminating in a press 5 through which are sealed a plurality of lead wires 6. Lead wires 6 are attached to terminals 3. Within container 1, and upon lead wires 6 are mounted a plurality of electrodes comprising a pair of cylindrical anodes 7 and 7', a pair of cylindrical helical grids 8 and 8' and a pair of filamentary cathodes 9 and 9'.

Anodes 7 and 7' are cylindrical in form, 20 each with a fin 11 at a place on its periphery extending the length of the cylinder. The fins 11 are attached to one of the wires 6 which are sealed in the press 5. Helical grids 8 and 8' are attached to supporting wires 12 and 12' 25 which, in turn, are attached to another of the wires 6 through press 5. The wire 6 to which the fins 11 of anodes 7 and 7' are attached has, upon the end within container 1, a glass bead 14 through which is sealed a supporting and lead wire 15. The free ends 30 of wire 15 support the upper ends of filamentary cathodes 9 and 9', the lower ends of which are attached to others of wires 6.

35 By means of the construction shown in the drawings and described, a pair of anodes is mounted upon a single lead wire through press 5 and electrically connected thereto. A pair of grids is likewise mounted upon another wire 6 and electrically connected thereto. The pair of anodes is connected in parallel as is the pair of grids. The pair of filamentary cathodes 9 and 9' is connected in series through the intermediary of wire 15. The structure as shown and described is 45 further completed by evacuation of air from container 1 through a tip seal 16.

In the operation of my device, filamentary cathodes 9 and 9' may be heated by current from dry batteries to a temperature at which 50 they emit electrons. An electron stream will then flow upon the application of voltage between the anode and the cathode. The electron streams between the cathode 9 and anode 7 and between cathode 9' and anode 7' are 55 then in parallel. The device thereby has a space current twice as great as would occur in a similar construction containing a single anode and cathode of the same size and type when the cathode was heated to a corresponding temperature and a similar voltage applied between cathode and anode. Furthermore, the vacuum surrounding both anodes, both cathodes and both grid electrodes is the same and, therefore, the operating characteristics of the two sets of electrodes are the

same in response to changes in applied potential and changes of grid potential.

By the structure described, I have produced a space current device in which a greater electron stream is obtainable and a greater anode current obtainable than in similar devices of the prior art. 70

In the modification of my invention shown in Figs. 2 and 5, the anode cylinders 8 and 8' are disposed in the plane of the press 5, the construction of the tube being otherwise similar to that shown in Figs. 1, 3 and 4. However, the latter construction, with the anode cylinders arranged in a plane perpendicular to the plane of the press, is deemed preferable 75 since it results in a simpler arrangement of the wire standard extending from the press to support the several electrodes; and reduces the interelectrode capacity of the tube. In both constructions, however, the two sets of 80 distinct electrode assemblies are positioned by the standards extending from only four lead-in wires which are fused in the press. The latter feature becomes very important in the construction of small tubes, since difficulties 85 are encountered when making presses having fused thereto more than four wires. The small number of press wires is, of course, very important in so far as it affects the interelectrode capacity of the tube. 90

95 While I have shown only two embodiments of my invention in the accompanying drawings, it is capable of various changes and modifications without departing from the spirit thereof, and it is desired, therefore, that only such limitations shall be imposed thereon as are indicated in the prior art or in the appended claims.

100 I claim as my invention:

1. An electron-discharge device comprising a flat press, a plurality of lead-in wires held in said press, and a plurality of sets of electrodes, each set comprising a cathode and an anode, each anode surrounding its respective cathode and all having their central axes disposed in a plane perpendicular to the plane of said press. 105

2. An electron-discharge device comprising a container, and a plurality of anode, grid and cathode elements assembled in a plurality of distinct parallel disposed sets, the central axes of said elements being in one plane, a press disposed in a plane perpendicular to said one plane, and a plurality of wires extending from said press for supporting said electrode sets and for making electrical connections therewith. 110

115 3. In an evacuated electron-discharge device, a pair of anodes, cathode elements and control electrodes associated with each of said anodes to constitute two distinct discharge paths, a press, and four lead-in wires extending from said press and constituting the electrical connections to, and the sole me- 120

125

chanical support of, the electrodes constituting said discharge paths.

4. An electron-discharge device comprising an evacuated container having a stem, three conductor elements insulatingly supported on said stem, and a plurality of anode and cathode elements constituting a pair of distinct discharge paths, said conductor elements constituting the sole support and the conducting terminal connections of the elements constituting said discharge paths.

5. An electron-discharge device comprising an evacuated container having a stem, four lead-in wires sealed into said stem and having extensions projecting into said container, a pair of cathode elements, distinct grid elements surrounding each cathode element, anode elements surrounding said cathode and grid elements and constituting therewith distinct electron-discharge paths, the extensions of three of said wires constituting the supports for said cathode elements, the extensions of two of said wires constituting the sole supports of said anode 25 and grid elements.

6. An electron-discharge device comprising a container having a press, a pair of parallel disposed tubular anodes, a pair of cylindrical grids and cathodes, respectively disposed within said anodes, and four leading-in wires sealed into said press and constituting the sole mechanical support, and the electrical connections, of said anode, grids and cathodes.

7. In an electron-discharge device, a pair of parallel standards, a pair of longitudinally extending cathode elements disposed in a plane perpendicular to the plane of said standards, a pair of grids individually surrounding each of said cathode elements, and tubular anode means surrounding said grids, said standards constituting the only supports for said grids and anodes.

8. An electron-discharge device comprising a press, a pair of longitudinally extending cathode elements disposed in a plane perpendicular to the plane of said press, a pair of grids, each grid surrounding only one of said cathode elements, tubular anode means surrounding said grids, and lead-in wires extending from said press and connected to said electrodes.

9. In an electron-discharge device comprising a press, a pair of parallel tubular anodes whose axes are disposed in a plane different from the plane of the press, cylindrical grids concentrically disposed within said anodes, longitudinal cathode elements, centrally disposed within said grids, a plurality of lead-in wires fused in said press, one of said lead-in wires being the common terminal connection of said anodes, another of said lead-in wires being the common terminal connection 65 of said grids, and still another of said lead-in

wires being one of the terminal connections of said cathode elements.

10. An electron-discharge device comprising an evacuated envelope having a press therein, an electrode having a plurality of cylindrical portions, a second electrode within each of said cylindrical portions and an electrical conducting support-arm extending through said press and supporting said electrodes.

11. An electron-discharge device comprising an evacuated envelope having a press therein, an electrode having a plurality of substantially cylindrical portions, a filament-electrode within each of said portions substantially concentric therewith and a support-arm which extends from said press and which is common to all of said electrodes and electrically connected to said first-mentioned electrode.

12. In an electron-discharge device, an electrode having a plurality of cylindrical portions, a cathode within each of said portions, a support-arm for said first mentioned electrode common to the portions thereof and means attached to said support-arm supporting all of said cathodes.

13. An electron-discharge device comprising an evacuated envelope having a press therein, an anode-electrode having a plurality of cylindrical portions, a second electrode within each of said cylindrical portions and a support-arm which extends from said press and which is common to all of said electrodes and electrically connected to said anode-electrode.

In testimony whereof, I have hereunto subscribed my name this 22nd day of August, 1924.
